(57) **CLAIM**

We claim the ornamental design for a rearview mirror for a vehicle, as shown and described.

DESCRIPTION

FIG. 1 is a front, top perspective view of a rearview mirror for a vehicle of the present disclosure;

FIG. 2 is a front, bottom perspective view of the rearview mirror of FIG. 1;

FIG. 3 is a rear, bottom perspective view of the rearview mirror of FIG. 1;

FIG. 4 is a front elevational view of the rearview mirror of FIG. 1;

FIG. 5 is a rear elevational view of the rearview mirror of FIG. 1;

FIG. 6 is a left side elevational view of the rearview mirror of FIG. 1;

FIG. 7 is a right side elevational view of the rearview mirror of FIG. 1;

FIG. 8 is a top plan view of the rearview mirror of FIG. 1; and,

FIG. 9 is a bottom plan view of the rearview mirror of FIG. 1.

The broken lines depict portions of the article that form no part of the claimed design.

1 Claim, 9 Drawing Sheets
